US00D856754S

(12) **United States Design Patent** (10) **Patent No.:** **US D856,754 S**
(45) **Date of Patent:** **** Aug. 20, 2019**

(54) **BEVERAGE CONTAINER**

- (71) Applicant: **Vinglacé, LLC**, Houston, TX (US)
(72) Inventor: **Colton Bryan Haas**, Houston, TX (US)
(73) Assignee: **Vinglacé, LLC**, Houston, TX (US)
(**) Term: **15 Years**
(21) Appl. No.: **29/661,461**
(22) Filed: **Aug. 28, 2018**

Related U.S. Application Data

- (63) Continuation of application No. 16/100,153, filed on Aug. 9, 2018.

(57) **CLAIM**

I claim the ornamental design of a beverage container, as shown and described.

DESCRIPTION

FIG. 1 is a front perspective view of a beverage container showing my new design;

FIG. 2 is a bottom perspective view of the beverage container of FIG. 1;

FIG. 3 is a left side view of the beverage container of FIG. 1;

FIG. 4 is a right side view of the beverage container of FIG. 1;

FIG. 5 is a rear view of the beverage container of FIG. 1; FIG. 6 is a front view of the beverage container of FIG. 1; FIG. 7 is a top plan view of the beverage container of FIG. 1; and,

FIG. 8 is a bottom plan view of the beverage container of FIG. 1.

The broken lines in the drawings depict portions of the beverage container that form no part of the claimed design.
